UNITED STATES PATENT OFFICE.

JOSEPH NELSON KELMAN, OF LOS ANGELES, CALIFORNIA.

SWITCH FOR HIGH-POTENTIAL CIRCUITS.

No. 874,601.

Specification of Letters Patent.

Patented Dec. 24, 1907.

Application filed April 8, 1907. Serial No. 367,124.

To all whom it may concern:

Be it known that I, JOSEPH NELSON KELMAN, of the city of Los Angeles, in the county of Los Angeles, in the State of California, have invented a certain new and useful Switch for High-Potential Circuits, the Same also Acting as a Circuit-Breaker, of which the following is a full, clear, and exact specification, reference being had to the annexed drawings, and to the figures and letters marked thereon.

My said invention which relates to switches for interrupting high potential circuits, and to act as circuit breakers, has for its object to provide an apparatus which is not only safe and effective in operation, and consequently can be depended upon at all times to open the circuit under any condition of overload or short circuit, is of that type of switches wherein the circuit is opened or closed under oil. I have tested my said switches and circuit breakers on electric systems ranging in voltages from 15,000 to 60,000 under all conditions of overload and short circuit. The switches are made up with any number of poles desired, with each pole in a separate tank and with a double horizontal contact breaker to each pole.

The device constituting my invention is contained within an iron tank, the top or cover of which is of marble and preferably made in two pieces, so that either or both of these pieces of marble can be readily taken off to admit of inspection of the switch in the interior of the tank, for the reason that the pieces of marble constitute a cover for the tank, none of the working parts being fixed to or supported by them in any respect.

The fixed contacts of the switches are mounted on porcelain insulators of special design as hereinafter described, giving very high insulation and considerable mechanical strength. These insulators are mounted upon a wooden support placed deep down in the oil in the tanks. The movable contacts of the switch are attached to a rod of specially treated wood, while between this rod and the operating mechanism is a porcelain insulator of special design and construction giving very high insulation at this part of my device.

The movement of the operating mechanism is in a vertical direction, but the break of the fixed and movable contacts is in a nearly, if not quite, a horizontal direction, taking place deep down below the top of the oil

contained in the tanks, so that there is a considerable volume of oil above the fixed and movable contacts, thereby rendering, on account of the high resistance of the oil, the break, and making the opening of the circuit, a certainty. The portions of the conductors connected to the fixed contacts of the switch are brought out through heavy porcelain insulators that stand well above the surface of the cover, thus affording ample insulation.

Upon the annexed drawings, Figure 1 is a front elevation of my device, showing the oil tanks wherein the stationary or fixed and movable contacts or poles of a three pole switch for hand operation, and constructed according to my invention, are contained. Fig. 2, is a plan corresponding to Fig. 1. Fig. 3, is an end elevation of the oil tanks with portions of the apparatus constituting my invention shown in dotted lines, and partly in full lines. Fig. 4, is a transverse section of one of the tanks on a larger scale than Figs. 1, 2, and 3, and showing the interior of the tank, and the switch mechanism. Fig. 5, is a vertical section on the central line *a*, *a*, at Figure 4. Fig. 6, is a vertical section on the line *b*, *b*, Fig. 4, and Fig. 7, is a horizontal section on the line *c*, *c*, Fig. 6, showing in plan the switch clips and switch blade entering the same.

In Figs. 1, 2, 3, and 4, the tanks containing the oil and the mechanism for making and breaking a high potential circuit are marked A. Each of the tanks A, rests upon the beams B, Fig. 3, of wood, iron, channel beams or other material. In each of the two spaces between the central and end tanks A, A, as shown at Figs. 1, and 2, and in dotted lines in Fig. 3, there are situated two A-shaped framings C, of cast iron, in the lower part of which the shaft D, is carried rotatively in bearings, as shown in dotted lines in Figs. 1, and 3, and in plan in Fig. 2. These A-shaped framings C, are firmly bolted to the beams B, upon which the tanks A, rest. Upon one end of the shaft D, an operating lever or handle E, is attached, and at the opposite end of the shaft D, the coöperating weight F, is also attached by a lever as shown at Figs. 1, and 2. Two other levers G, G, are fastened upon the shaft D, and are each connected pivotally by a link H, shown in dotted lines at Fig. 3, to the lower end of each lifting rod I, to the upper part of which the channel iron J, is securely fastened, and connects

the vertical rods I, I, together. The channel iron J, is also connected at its ends, and at its center by strong porcelain insulators K, to a thick rod L, of specially treated wood, and the lower end of the thick wooden rod L, is connected to the two movable blades or switch arms M, which make and break contact with the fixed poles N, N, of the switch. The arms M, M, are pivotally connected by the bolts O, O, to the attachment P, fastened by bolts or rivets P', to the lower part of the wooden rod L, and the switch blades M, M, are again connected by the pivotally jointed links Q, Q, to the upper central part of the insulator K, fastened to the wooden rail S, stretching across the bottom of each of the tanks A, more especially as shown at Fig. 4, and at Figs. 5, and 6. To the fixed contacts or poles N, the portions of the circuit T, which enter the switch are connected, and these portions T, pass out through the cover of each tank through insulators T'. Each of the two blades or switch arms are respectively united at their upper parts by means of a piece of flexible cable U, the ends of which are metallically and rigidly connected to the two blades or switch arms by the bolts U', as shown at Figs. 4, and 5.

30 The construction of the insulators T', through which the conductors T, pass, is illustrated in section at Fig. 6, consisting as more especially shown at Fig. 6, of the inner and upper porcelain part V, through which 35 one of the conductors T, pass. This portion V, is flanged at the top so that it may rest securely upon the lower part V', of the insulator which again is formed with a flange so as to rest upon the top of the slate or marble 40 cover W, of the tanks A.

The insulators K, are of special construction as shown more especially in section at Figs. 5, and 6, and are connected to the wooden beams S, within the tanks A, by the 45 clips next to be described. As shown by Fig. 2, more especially, the insulators K, are circular in plan, and their upper and lower parts, as shown by Figs. 5, and 6, more especially, are tapered inwards, that is to 50 say, the portion of largest diameter of the upper and lower part of each insulator K, constitutes the uppermost and lowermost face of the insulator. The clips by which the insulators K, are held to the several 55 parts of my switch and circuit breaker apparatus, are made in two halves of cast iron marked X, and Y, respectively, as particularly shown at Fig. 4, and upon these parts of the clips X, and Y, lugs X', and Y', are 60 formed, and as shown at Figs. 5, and 6, each half of the clips X, and Y, has a flat face parallel with the inner faces of the projecting lugs, while the form of the interior of the 65 projecting lugs is inclined but in the opposite direction of inclination of the inclined

interior of the clips, so that when the bolts Z, are put through the holes in the lugs, the tightening of the nuts thereon pulls the two halves of each clip together and causes the inclined surfaces of the interior of each clip, 70 and the exterior of each insulator to hold firmly together, and so that the pressure of the clip upon the insulator may be as near as possible equally transmitted all around the brittle material (porcelain) of which the 75 insulators K, are made. A lining of soft material such as is shown at d, in Figs. 5, and 6, is inserted, and the tightening of the bolts Z, takes place around the soft material d, which may be lead or an insulating material. 80 The clips X, by which the several insulators K, are fastened to the wooden beam S, or to the channel iron J, are secured thereto by means of tap bolts Z', as shown at Figs. 5, and 6. The upper part A', of each tank 85 A, is preferably formed of slate, marble, or other suitable insulating material, and it is constructed in two halves as illustrated by the lines e, e, in Fig. 2, so that either portion of the cover of the tank may from time to 90 time be removed for the purpose of examining the interior of the tank and the state or condition of the switch apparatus therein.

When the circuit of which the conductors T, T, form part, is in operation, then the 95 switch blade M, the links Q, the wooden rod L, and the poles or contacts N, are all in the relationship shown in the enlarged view Fig. 4, and when it is desired or necessary to open or break the circuit, then the switchman or 100 attendant pulls or presses downwards the lever handle E, fixed to the shaft D, in which act he is assisted by the weight F, also carried by a lever on the shaft D. The effect of this pull or push downwards of the switch- 105 man upon the lever E, is to raise upwards the rods I, the channel iron J, the upper insulators K, and their connections, together with the wooden rods L, through the ferrules W', and thence by pulling vertically up- 110 wards upon the switch blades M, M, by the pivotal connections O, O, to gradually draw the terminals of the switch blades M, M, out of the contact pieces or poles N, N, until the contact of the switch blades M, M, with the 115 contact pieces or poles N, N, is broken, when the arc produced at the instant of opening the contact takes place deep down in the body of oil contained within the tank A.

In order that the separation of the contact 120 portions of the switch blades M, M, and those of the poles or fixed contacts N, N, may take place in a direction of movement as nearly horizontal as possible, the switch blades M, M, are pivotally connected as aforesaid by 125 the two links Q, Q, to the upper end of the central lower insulator K, so that while the upward movement of the wooden rods L, during the act of completely opening the switch or circuit breaker takes place, the 130

links Q, in being drawn closer together at the same time draw the switch blades M, M, closer together as shown by the dotted lines in Fig. 4, thus maintaining the ends or contact pieces of the blades M, M, as low down as possible in the oil in the tanks A, during the time the switch is being completely opened, and after it is completely opened.

As it is the fact that in high potential electrical circuits there is a tendency for leakage of the charge or current to take place over surfaces however slightly moist, and as there is always a tendency for moisture to condense upon surfaces which are of a low temperature, the insulators K, used in my apparatus are preferably constructed with wide and thin flanged surfaces projecting from the central body of the insulator as shown at Fig. 5, the object of thus forming the insulator being to provide as large a surface as possible for moisture to condense upon, and for the wind or atmospheric heat to dry up as much as possible, thereby leaving as little moisture as possible upon the insulator for electrical leakage to take place.

I claim in my invention.

1. The switch and circuit breaker for high potential circuits, consisting of two or more pairs of horizontally projecting poles or contact pieces with which oppositely operating switch blades make and break contact, the upper ends of each pair of said blades being connected to a rod of wood or equivalent insulating material, said switch blades being pivotally connected near their center of length by links to pivotal connections on an insulator, attached to a beam of wood at the bottom of the tank, the fixed poles or contact pieces being also attached to insulators fastened to a wooden beam within the tank, the conductors from the fixed poles or contact pieces extending through insulators carried in the top cover of the tank, consisting of non-conducting ma-

terial, the ferrules of insulating material at the center of the cover of the tanks, the wooden rods operating in said ferrules, the clips connecting an insulator with the top of the wooden rod, the clips connecting the insulator to the channel iron, the connecting pieces and pivots by which the lower end of the wooden rods are connected to the upper parts of the switch blades, a flexible connection between the upper ends of the switch blades, the frames and guides between the center tank and each of the side tanks, the vertical rods operating in said frames and guides, the shaft, the lever and links and the counter weight for opening and closing the switch or circuit breaker, all operating in the manner and for the purposes substantially as hereinbefore described.

2. The combination of the channel iron, the clips connecting the channel iron to the upper parts of the insulators, clips connecting the lower part of the upper insulators with the upper end of each wooden rod, the wooden rods, the connecting piece at the lower end of each wooden rod, to which the switch blades are pivoted, the flexible metallic connection between the upper pivoted ends of the switch blades, the switch blades, the links pivotally connecting the switch blades to the stationary insulator, so that the ends of the switch blades operate horizontally, or nearly so, in opening and closing the circuit to the fixed poles or contact pieces, substantially as hereinbefore described.

In testimony whereof, I have hereunto set my hand and seal at the city of Los Angeles aforesaid, in the presence of two subscribing witnesses.
